MEAT TENDERIZER

William Marcus, Cleveland, Ohio

Application June 10, 1954, Serial No. 30,906

Term of patent 7 years

(CL. D44—29)

Fig. 1

Fig. 2

Fig. 3

To all whom it may concern:

Be it known that I, William Marcus, a citizen of the United States, residing at Cleveland, county of Cuyahoga, and State of Ohio, have invented a new, original, and ornamental Design for a Meat Tenderizer, of which the following is a specification, reference being had to the accompanying drawing, forming a part hereof.

Fig. 1 is a top plan view of a meat tenderizer showing my new design;

Fig. 2 is a side elevational view thereof;

Fig. 3 is a bottom plan view thereof.

I claim:

The ornamental design for a meat tenderizer, as shown.
